Primary Examiner — Martie K Holtje(74) *Attorney, Agent, or Firm* — Dwayne E. Rogge; Schacht Law Office, Inc.(57) **CLAIM**

The ornamental design for asymmetric aircraft luggage bin faces, as shown and described.

DESCRIPTION

FIG. 1 is a perspective view of asymmetric aircraft luggage bin faces showing my new design; and, FIG. 2 is an end view thereof.

The structural elements depicted by broken lines have been shown for the purpose of illustrating portions of the asymmetric aircraft luggage bin faces that form no part of the claimed design.

The end opposite FIG. 2, not shown, forms no part of the claimed design.
